UNITED STATES PATENT OFFICE.

JOSEPH L. R. HAYDEN, OF SCHENECTADY, NEW YORK, ASSIGNOR TO GENERAL ELECTRIC COMPANY, A CORPORATION OF NEW YORK.

VAPOR ELECTRIC DEVICE.

1,006,657.

Specification of Letters Patent. Patented Oct. 24, 1911.

Application filed April 16, 1907. Serial No. 368,490.

To all whom it may concern:

Be it known that I, JOSEPH LE ROY HAYDEN, a citizen of the United States, residing at Schenectady, county of Schenectady, State of New York, have invented certain new and useful Improvements in Vapor Electric Devices, of which the following is a specification.

A certain class of vapor electric devices, more particularly those used on high potential currents, must be maintained in such a state of evacuation that the arc path will be relatively free from foreign gases. The presence of gas is likely to produce rapid deterioration of the tube and reduce its reliability. In general the tube can be very satisfactorily evacuated during the process of manufacture, but unfortunately this state of vacuum is not permanent, possibly because of the liberation of gases by the electrodes of the tube.

According to my present invention, the foreign gases of the tube are segregated in the condensing chamber or in some other part of the tube where they are out of the direct path of the arc. This segregation may be produced by covering or inclosing a portion of the condensing chamber with a metal covering or shell connected to a point having a potential different from that of the gases or vapors in the rectifier tube. By this means the gases are held in the condensing chamber by electrostatic attraction and are thus kept out of the path of the vapor arcs.

An embodiment of my invention is illustrated in the drawing forming a part of this specification.

This drawing illustrates a constant current rectifier provided with an electrostatic attracter.

The mercury rectifier may be of an ordinary type comprising a central condensing chamber 1, anode arms 2 and 3, and a mercury cathode 4. The anode arms 2 and 3 preferably converge immediately above the cathode 4 and communicate with the condensing chamber 1 through a relatively small opening 5. When current is passing through the tube in normal manner, arcs are produced to cathode 4 from anodes 6 and 7.

A rectifier of the type above described is suitable for converting alternating current into direct current to supply a constant cur-

rent load. The alternating current source may consist of a transformer of ordinary type having a secondary with its terminals connected directly to anodes 6 and 7 and with a central tap 10 connected to one side of the load circuit 11. The cathode blast of the arc tends to carry foreign gases directly upward through opening 5 and into the condensing chamber, so that the arc naturally tends to keep foreign gases out of the anode arms. 60

So long as the quantity of gas within the tube remains low, the arc will gradually segregate the gases in the condensing chamber, but if for any reason the quantity of gas is suddenly augmented, this segregation of foreign gases may not be rapid enough to prevent the rectifier from "fading" or gradually going out. To insure a more rapid segregation of foreign gases and to provide 75 for the retention of these gases in the condensing chamber, I place a metal shell 12 about a portion of the condensing chamber, as over the end thereof, and I electrically charge this shell by connecting it to one of 80 the conductors of the system and preferably to the load circuit on the side nearest the transformer tap 10. In my opinion this metal shell 12 exerts an electrostatic attraction for the gases within the condensing 85 chamber 1 and so materially assists in removing foreign gases from the direct path of the arcs in anode arms 2 and 3. Furthermore, this electrostatic attraction holds the gases in the condensing chamber and prevents diffusion thereof into other parts of 90 the tube.

The metal shell 12 may be shaped substantially like the upper end of the condensing chamber 1, and may be supported 95 therefrom by adjustable set screws 13 having wooden tips 14. I prefer to perforate the shell and to make the lower part bell-shaped or flaring.

What I claim as new and desire to secure 100 by Letters Patent of the United States, is,—

1. In a vapor electric device co-operating electrodes, an evacuated envelop having a condensing chamber situated opposite a negative electrode and extending away from 105 said electrode and a conductive member surrounding a remote portion only of said condensing chamber to electrostatically keep gases therein out of the path of the arc.

2. In a vapor electric device having an 110

evacuated envelop comprising one or more arc chambers and a condensing chamber communicating therewith through a relatively small opening, the combination of 5 means for electrostatically attracting gases contained in said condensing chamber to restrain their diffusion to the arc chambers.

3. In a mercury vapor rectifier, the combination of coöperating electrodes, a condensing chamber communicating through a relatively small opening opposite the cathode with the space surrounding said electrodes and a metal shell inclosing a portion of the condensing chamber remote from said opening to electrostatically attract gases segregated within said envelop and means for

maintaining said shell at a potential differing from the cathode.

4. The combination of a constant current transformer, a vapor rectifier having anodes 20 connected with said transformer, a load circuit connected with the cathode of said rectifier and with a neutral point on said transformer, and a metal shell inclosing a portion of said rectifier and electrically connected 25 with said neutral point.

In witness whereof, I have hereunto set my hand this 13th day of April, 1907.

JOSEPH L. R. HAYDEN.
